US00D906167S

(12) **United States Design Patent** (10) Patent No.: **US D906,167 S**
(45) Date of Patent: **** Dec. 29, 2020**

(54) **FASTENER FOR ACCESSORIES**

(71) Applicant: **Houseki-no-Angel Co., Ltd.**, Aichi (JP)

(72) Inventor: **Hisaziro Hashimoto**, Nisshin (JP)

(73) Assignee: **Houseki-no-Angel Co., Ltd.**, Nagoya (JP)

(**) Term: **15 Years**

(21) Appl. No.: **35/507,575**

(22) Filed: **Feb. 20, 2019**

(80) **Hague Agreement Data**

Int. Filing Date: **Feb. 20, 2019**

Int. Reg. No.: **DM/203445**

Int. Reg. Date: **Feb. 20, 2019**

Int. Reg. Pub. Date: **Oct. 25, 2019**

(30) **Foreign Application Priority Data**

Aug. 25, 2018 (JP) 2018-018523

(51) **LOC (12) Cl.** **11-01**

(52) **U.S. Cl.**

(57) **CLAIM**

The ornamental design for a fastener for accessories, as shown and described.

DESCRIPTION

1. Fastener for accessories

1.1 : Perspective

1.2 : Reference

1.3 : Reference

1.4 : Reference

1.5 : Perspective

1.6 : Front

1.7 : Top

1.8 : Left

1.9 : Right

1.10 : Perspective

1.11 : Front

1.12 : Top

1.13 : Back

1.14 : Left

1.15 : Right

The fastener for accessories is composed of a female part showing in the reproductions 1.10 to 1.15 and a male part

(Continued)

showing in the reproductions 1.5 to 1.9; the bottom view of the female and male parts are omitted because they are a mirror image of the top view; the back view of the male part is omitted because it is a mirror image of the front view; The chain and the pendent shown in reproductions 1.2, 1.3 and 1.4 form no part of the claimed design.

1 Claim, 15 Drawing Sheets
